CLAIM

(51) **LOC (13) Cl.** **13-02**

The ornamental design for a dye-sensitized solar cell module, as shown and described.

(52) **U.S. Cl.**

DESCRIPTION

USPC **D13/102**

FIG. 1 is a front elevation view of a dye-sensitized solar cell module according to our design;

(58) **Field of Classification Search**

FIG. 2 is a rear elevation view of the dye-sensitized solar cell module of FIG. 1;

USPC D13/102, 101, 110, 118, 133, 182, 184,

FIG. 3 is a top plan view of the dye-sensitized solar cell module of FIG. 1;

D13/199

FIG. 4 is a bottom plan view of the dye-sensitized solar cell module of FIG. 1;

CPC H01L 31/02; H01L 31/042; H01L 31/048;

FIG. 5 is a right side elevation view of the dye-sensitized solar cell module of FIG. 1; and,

H01L 27/142; H01L 27/1421; Y02E

FIG. 6 is a left side elevation view of the dye-sensitized solar cell module of FIG. 1.

10/40; Y02E 10/47; Y02E 10/50; Y02E

The broken lines shown in the drawings depict portions of
